STREET CAR SIGNALING DEVICE

Charles Walker, Knoxville, Tenn.

Application June 22, 1932, Serial No. 618,641

5 Claims. (Cl. 40—55)

My invention consists in new and useful improvements in a signaling device used in connection with street cars, buses and other passenger vehicles to indicate to the passengers the names 5 of the streets as they are crossed by the vehicle.

It is the object of my invention to provide an 10 electrically controlled indicating unit located in the passenger compartment of a vehicle automatically operated by a remotely located mechanism.

Another object of my invention is to provide a 15 mechanism controlled by the motorman or operator of the vehicle for simultaneously actuating the indicating unit.

A still further object of my invention resides in 20 the combination with a mechanically actuated indicating device for the operator of the vehicle, of an electrically controlled indicating unit for the passenger compartment, the latter being actuated through the medium of and to a corresponding extent, with the mechanically operated device.

With the above and other objects in view which 25 will appear as the description proceeds, my invention consists in the novel features herein set forth, illustrated in the accompanying drawings and more particularly pointed out in the appended claims.

Referring to the drawings in which numerals of 30 like character designate similar parts throughout the several views,

Fig. 1 is a longitudinal vertical section through 35 the front end of a street car showing the indicating unit and controlling mechanism in place.

Fig. 2 is a front elevation of the indicating unit 40 with the operating mechanism shown in dotted lines.

Fig. 3 is a front elevation of the controlling mechanism.

Fig. 4 is a section taken along lines 4—4 of Fig. 1.

Fig. 5 is a top plan view of the mechanism shown in Fig. 3, and

Fig. 6 is a fragmentary detail of the belt carrying the names of the streets.

In the drawings, referring particularly to Fig. 45 1, numeral 1 indicates the floor of a street car on which is mounted a conventional control box 2. A pair of vertically extending brackets 3 suitably secured to said control box 2 are drilled transversely adjacent their upper extremities and adapted to support a transverse shaft 4 and form bearings therefor. A drum 5 fixed to the shaft 4 carries a plurality of indicia of the names of the streets crossed by the street car, said drum being surrounded by a housing provided with an opening 50 or window 48 to present the name of the

street to the view of the operator. Adjacent one end of the drum 5 I provide a pinion gear 6 also keyed to the shaft 4 to cause the rotation of the shaft and drum as hereinafter set forth.

A second transverse shaft 7 supported in bearings formed by the brackets 3 and located at a suitable point below the shaft 4, extends outwardly beyond one of the brackets 3 and carries a second gear 8 adapted to mesh with the gear 6 on the shaft 4. The projecting end of the shaft 7 carries two spaced ratchet wheels 9 and 10, the respective teeth of which extend in opposite directions.

12 represents a guide yoke supported on a suitable bracket 11 which in turn is mounted on the upper end of the control box 2, said guide yoke being adapted to loosely support a pair of rods 13 and 14 provided with teeth adapted to engage the complementary teeth on the ratchets 9 and 10, respectively, and normally forced 15 toward said ratchets by suitable spring members 13a and 14a, respectively, carried by the yoke 12. Springs 15 and 16 normally hold the rods 13 and 14, respectively, in inoperative position, with the teeth on the rods out of engagement with the 20 respective ratchet wheels. It will be observed that rod 13 lies above ratchet wheel 9, while rod 14 lies beneath ratchet wheel 10.

The inner ends 17 and 18 of the respective rods 25 13 and 14 are adapted to contact electrodes 19 and 20, respectively. These electrodes are suitably mounted on the front wall 21 of the street car at a point below the window 22, for the purpose hereinafter set forth.

At a suitable point on the wall 23 which separates 30 the motorman compartment from the passenger compartment, I mount a housing 24 for the indicating unit. Disposed transversely within said housing is a shaft 25 reduced adjacent its extremities to fit in bearings 26 formed 35 by the side walls of the housing 24, said shaft carrying a drum 27, the opposite extremities of which are provided with sprocket wheels 28.

Also disposed transversely within said housing 40 24 at a suitable point below the shaft 25, I 45 provide a second shaft 29 carrying a drum 30 also provided with sprocket wheels 31. An endless belt 32 carrying a plurality of indicia corresponding to the indicia on the drum 5, is adapted to travel around the two drums 27 and 50 30, perforations 33 being provided along the longitudinal edges of said endless belt to engage the sprockets 28 and 31, respectively, to insure positive rotation of the belt.

As shown in Fig. 4, the shaft 25 carries two 55

ratchet wheels 34 and 35 with the teeth of the respective ratchets extending in opposite directions.

Referring back to Fig. 1, it will be seen that I provide two vertically spaced longitudinally extending brackets 36 and 37 secured to the rear wall of the housing 24 by means of screws 38, said brackets 36 and 37 being vertically drilled to slidably support oppositely disposed resilient pawl rods 39 and 40, pawl rod 39 being adapted to engage the ratchet 35, and pawl rod 40 to engage ratchet 34. Springs 41 and 42 suitably mounted on the pawl rods 39 and 40, respectively, in abutting relation with the adjacent surfaces of the respective brackets 36 and 37, normally hold said pawl rods in inoperative position with their teeth out of engagement with the ratchet wheels.

The pawl members 39 and 40 terminates at one end in armatures 39a and 40a and are actuated by electro-magnets 43 and 44, respectively, located adjacent the bottom and top walls of the housing 24, said electro-magnets being in circuit with the electrodes 19 and 20, respectively, located adjacent the control box 2.

A window 47 is provided in the front wall of the housing 24 at a suitable point adjacent the belt 32 to enable the passengers to see the names of the streets as the drums 27 and 30 rotate.

The opposite ends of the respective pawl rods 39 and 40 project through suitable openings in the brackets 36 and 37, said openings being provided with spring members 45 and 46 interposed between the outer surfaces of the pawl rods and the adjacent surfaces of the brackets, said springs normally tending to retain the pawl rods in position for engagement with the respective ratchet wheels 34 and 35.

Having thus described the construction of my invention, its operation is as follows:—

Assuming that the street car is about to begin its run down town and that Jackson is the first street crossed. After crossing Jackson Street, the motorman will push rod 14 inwardly against the action of the spring 16, the teeth on said rod engaging the teeth on the ratchet 10, and through the medium of gears 6 and 8, will rotate the drum 5 one degree in clockwise direction and bring the name of the second street (Clark) opposite the window 48. Simultaneously with this operation, the contact of the inner end 17 of the rod 14 with the electrode 19 completes the circuit to the electro-magnet 43, energizing the same and actuating the pawl 39 downwardly, the teeth on the latter engaging ratchet 35, thus rotating the drum 27 one degree in clockwise direction and bringing the name of the next street (Clark) into view. It will be noted that the electro-magnet is only momentarily energized since the release of the rod 14 will cause the same to be brought back to normal position by the action of the spring 16 and will immediately break the circuit, the spring 14a permitting the rod 14 to slide past the teeth on the ratchet. Simultaneously with this operation, the spring 41 returns the pawl 39 to its normal inoperative position, spring 46 permitting the teeth on said pawl to slide past the ratchet teeth to a position out of engagement therewith. This operation is repeated throughout the entire down town run of the vehicle.

Upon the completion of the down town run and on the return trip of the vehicle to its starting point, the motorman will successively push the rod 13 inwardly as each street is crossed, thus rotating the drum 5 in counterclockwise

direction. As before stated, the teeth on ratchet wheel 9 are oppositely disposed from those on ratchet 10 so that a reverse action takes place upon the operation of the rod 13. The inner end 18 of the rod 13 contacts electrode 20 and completes the circuit to the electro-magnet 44, energizing the same. In this operation of the device, the pawl 40 will be moved upwardly and the teeth will slip over the ratchet wheel 34 against the pressure of the spring 42, and upon the release of the push rod 13, the electro-magnet 44 will be deenergized. The action of the spring 42 will then force the pawl 40 back to its normal position, causing the teeth on the pawl 40 to engage the ratchet 34 and rotate the same one degree, which in turn rotates the drum 27 in counterclockwise direction a like distance, bringing the next street into view.

While I have shown and described the belt 32 carrying a plurality of indicia, as being endless and rotating about two drums, it will be observed that this belt may be composed of a long strip with its free ends adapted to lie in receptacles provided in the bottom of the housing 24. In fact, my invention contemplates any type of indicating device adapted to be employed in the combination herein set forth, and I do not intend to limit myself to any of the specific details illustrated.

It will be further noted that while I have shown this device as applied to a street car, the same may be used in connection with any passenger vehicle with equal effect.

From the foregoing it is believed that the construction and operation of my invention may be readily understood by those skilled in the art without further description, it being borne in mind that numerous changes may be made in the details disclosed without departing from the spirit of the invention as set forth in the following claims.

What is claimed is,

1. A passenger vehicle signaling device comprising an indicator located adjacent the vehicle controller, a second indicating device located in the passenger compartment of said vehicle, said first named indicator comprising a rotary drum carrying a plurality of indicia arranged successively to represent the streets traversed by said vehicle, a ratchet operatively connected with said drum, an operating member provided with a pawl adapted to engage said ratchet, said second indicating device comprising a drum carrying a plurality of indicia corresponding to the indicia on said first named drum, a ratchet operatively connected to said second drum, an operating member provided with a pawl adapted to engage said ratchet, an electro-magnet operatively associated with said last named operating member, and means controlled by said first named operating member for completing an electric circuit to energize said electro-magnet, whereby said drums are caused to rotate simultaneously to present corresponding indicia to view.

2. A passenger vehicle signaling device as claimed in claim 1 wherein each of said indicator drums is enclosed in a casing, said casings being provided with windows through which said indicia are successively presented to view.

3. A passenger vehicle signaling device as claimed in claim 1 wherein each of said indicator drums is enclosed in a casing, said casings being provided with windows through which said indicia are successively presented to view, at least

one of said indicators including an elongated flexible tape carrying said indicia, said tape passing over the respective drum, and means whereby the rotation of said drum will advance said tape 5 to successively display the individual indicia thereon.

4. A passenger vehicle signaling device as claimed in claim 1 wherein each of said indicators is provided with two ratchets, one adapted to rotate the respective drum in one direction, and the other to rotate said drum in the opposite direction, and separate operating members and pawls for the respective ratchets.

5. A passenger vehicle signaling device comprising an indicator adapted to be located in the passenger compartment of a passenger vehicle, said indicator including a housing provided with a window, a drum mounted horizontally in said housing adjacent said window, an elongated flexi-

ble tape passing over said drum and carrying a plurality of indicia successively arranged to correspond with the streets traversed by said vehicle, a ratchet operatively connected to said drum, an operating member provided with a pawl adapted to engage said ratchet to rotate said drum in one direction, a second ratchet operatively connected to said drum, a second operating member carrying a pawl adapted to engage said second ratchet to rotate said drum in the opposite direction, electro-magnets operatively associated with said operating members, and means located adjacent the controller of said vehicle for energizing said electro-magnets, said last named means including a second indicator 10 adapted to display to the operator, indicia corresponding to that displayed by said first indicator. 15

CHARLES WALKER.
